UNITED STATES PATENT OFFICE.

JOHN TREGONING, OF NEW HAVEN, CONNECTICUT.

COMBINATION SASH-LOCK AND ALARM.

1,093,955.

Specification of Letters Patent. Patented Apr. 21, 1914.

Application filed November 27, 1912. Serial No. 733,903.

To all whom it may concern:

Be it known that I, JOHN TREGONING, a citizen of the United States, residing at New Haven, in the county of New Haven and State of Connecticut, have invented certain new and useful Improvements in Combination Sash-Locks and Alarms, of which the following is a specification, reference being had to the accompanying drawings.

10 This invention relates to an improved combination sash lock and alarm and has for its object to provide a device which may be easily and quickly applied to the window frame and the sashes and which will 15 admit of said sashes being opened to a limited extent, said locking means being included in an electric circuit, the circuit being closed to sound the alarm upon an attempt to move the sashes, in order to gain 20 access to the apartment.

Another and more specific object of the invention is to provide a movable arm or barrier disposed above the top bar of the lower sash, and resting at one end against 25 the upper sash, and a stop member carried by the upper sash with which said barrier is adapted to be engaged when the lower sash is raised, and circuit wires connected 30 to said stop member and the barrier to close an electric circuit and sound the alarm.

Still another object of the invention is to produce a device of the above character which is extremely simple in its construction, may be produced at small cost and is 35 highly efficient and positive in operation.

With the above and other objects in view as will become apparent as the description proceeds, the invention consists in certain 40 constructions, combinations and arrangements of the parts that I shall hereinafter fully describe and claim.

For a full understanding of the invention, reference is to be had to the following description and accompanying drawings, in 45 which—

Figure 1 is a fragmentary elevation of the inside of a window frame and sashes, showing my combination lock and alarm device applied thereto. Fig. 2 is a section taken on the line 2—2 of Fig. 1; Fig. 3 is 50 a view similar to Fig. 2, illustrating a slightly modified form of the device; and Fig. 4 is a fragmentary plan view of the lower sash and the stop member or barrier 55 illustrated in Fig. 3.

Referring in detail to the drawings, 5 des-

ignates a window frame or casing and 6 indicates the molding or guide strip for the lower window sash which is designated by the numeral 7. The usual parting bead 6' is 60 formed on the sides of the frame 5 and separates the lower sash 7 from the upper sash 8.

A movable arm or barrier 9 has one of its ends pivotally mounted upon the shank 65 of a screw 10 which is threaded in the molding strip 6 of the frame 5. This barrier arm is adapted when in its operative position, to extend transversely across the top bar of the lower sash 7, as clearly shown in Fig. 2, the free end of said bar resting against the upper sash, said bar being disposed at an inclination as shown so as to effectually prevent lowering of the upper sash from the exterior. This free end of 75 the barrier arm 9 is provided upon its upper edge with a flattened face 11 which is adapted to abut squarely against the lower end of a stop plate 12. This stop plate is secured to one of the stiles of the upper sash 8 by means of the screw 13, said plate, however, being capable of swinging movement upon the screw to the position shown in dotted lines in Fig. 1, so that the sashes may be raised or lowered relative to each 85 other. The barrier arm 9 and the stop plate 12 are each provided with an orifice to receive metallic plugs or tips upon the ends of the circuit wires 14 and 15, respectively, 90 said wires extending from the opposite poles of an electric battery indicated at 16. In the battery circuit, a bell or other alarm device indicated at 17 is arranged.

In the operation of the device as above described, the barrier arm is normally disposed upwardly at an angle from its pivoted end and rests at its free end against the upper sash. This bar is so located that the lower sash may be elevated to a point just beneath said bar in order to ventilate the 100 apartment, in which position the lower sash is shown in Fig. 2. Upon the attempt to elevate the lower sash beyond this point so as to gain access to the apartment, the top bar of said sash contacts with the lower edge 105 of the barrier arm 9 and forces the free end thereof upwardly into engagement with the lower end of the plate 12 on the upper window sash, thus closing the electric circuit and ringing the alarm bell. When the barrier arm is in its normal position and engaged with the upper sash, any downward

movement of said sash is rendered impossible, while any attempt to raise the lower sash above its adjusted position will move the arm 9 into engagement with the plate 12 and close the alarm circuit.

6 The slight space between the free end of the barrier arm and the plate 12 allows said plate to be swung to the dotted line position shown in Fig. 1, so that the barrier may be 10 swung to an inoperative position as shown in dotted lines in Fig. 3 to allow of the free sliding movement of both sashes. It will also be obvious that by this relative arrangement of the arm 9 and the plate 12, the electric circuit is normally open. A strip of 15 insulating material indicated at 18 is secured to the top bar of the lower sash upon which the barrier arm 9 engages. Suitable insulation is also provided between this arm 20 and the window frame and between the stop plate 12 and the stile of the sash 8.

In Fig. 3 of the drawings, I have illustrated a slightly modified form of the invention whereby ventilation may be had at 25 the top as well as the bottom of the window. In this modified form, I provide a stop plate 19 which is secured to the top bar of the lower sash by means of the screw 20 and projects from said sash bar beneath the plate 30 12' secured to the upper window sash. The pivoted barrier arm 9 is shown in its inoperative position, and the plate 19 has been swung from the dotted line position shown in Fig. 4 to the full line position in which 35 the end of said plate is disposed in the path of the plate 12'. By means of this arrangement, the upper sash may either be lowered until the end of the plate 12' is disposed closely adjacent to the plate 19, or said sash 40 lowered a less extent and the lower sash raised. Thus the movement of both sashes may be obtained, the extent of such movement being approximately equivalent to one half of the space between the plates 12' and 45 20 when the sashes are closed. It is understood that this additional stop plate 19 is to be used in connection with the barrier arm 9 so that ventilation may be obtained at either the top or bottom of the window 50 or at both the top and bottom. When the arm 9 is used, the plate 19 is swung to its inoperative position shown in dotted lines in Fig. 4 and said arm swung across the top bar of the lower sash as shown in Fig. 2. In 55 order to dispose the arm 9 in its inoperative position shown in dotted lines, the plate 12 is first swung to the dotted line position shown in Fig. 1 so that said arm may be lifted and swung to the dotted line 60 position shown in Fig. 1 so that said arm may be lifted and swung inwardly out of the path of movement of the lower sash. Both sashes can then be adjusted to any extent desired.

65 From the foregoing, it is believed that the

construction and manner of operation of my improved combination sash lock and alarm device will be clearly understood. Owing to the simplicity of the invention, it will be obvious that the same may be manufactured 70 at comparatively small cost and may also be readily applied to windows of the present construction without necessitating any material alteration therein. As all of the operating parts are disposed upon the inside 75 of the window, access cannot be had thereto from the exterior, so that the sounding of the alarm upon the attempt to open the window to such an extent, as would permit of access to the apartment, is positively assured.

It will of course, be obvious that the device is not necessarily limited in its application to the particular forms of the several elements as illustrated, but the proportions 80 and structural features thereof may be varied as special circumstances may suggest, without departing from the essential features of the invention or the scope of the appended claims.

Having thus described the invention, what is claimed is:

1. The combination with a window including upper and lower sashes, of a stop plate carried by the upper sash, a barrier arm pivoted upon the frame and extending across the top bar of the lower sash, an electric circuit, and an alarm device in said circuit, the terminal wires of the circuit being connected to said arm and to the plate, respectively, the elevation of the lower sash engaging the arm with said plate to close the circuit and sound the alarm.

2. The combination with a window frame and upper and lower sashes, of a circuit closing element mounted upon one of said parts, a stop plate carried by the upper sash, said circuit closing element having one of its ends projecting over the lower sash and disposed in the path of movement of said stop plate, whereby said element is brought into contact with said plate when the lower sash is raised, said element being pivotally mounted at one of its ends and movable with respect to the lower sash out of the path of movement of said stop plate to render the device inoperative, an electric circuit, the terminal wires of which are connected to the stop plate and the circuit closing element respectively and an alarm device in said circuit.

3. The combination with a window frame and upper and lower sashes therein, of a stop plate mounted upon the upper sash for swinging movement, a barrier arm pivotally mounted at one of its ends upon the frame and adapted to extend across the top bar of the lower sash, an electric circuit, the terminals of which are connected to the stop plate and arm, respectively, an alarm de- 125

vice in said circuit, the elevation of the lower sash moving said arm in an arcuate path and engaging the free end thereof with said plate to close the circuit and sound the alarm, said stop plate being adapted to be swinging upon the upper sash to permit of the swinging movement of the barrier arm upon its pivot to an inoperative position.

4. The combination with a window frame 10 and upper and lower sashes therein, of a stop plate carried by the upper sash, a circuit closing element pivotally mounted upon the window frame and extending over the lower sash, the free end of said element 15 normally resting against the upper sash be-

neath the stop plate and acting to prevent said upper sash from being lowered, an electric circuit, the terminal wires of which are connected to said plate and element, respectively, and an alarm device in said circuit, 20 the raising of the lower sash beyond a predetermined point engaging said element with said plate to close the circuit and sound the alarm.

In testimony whereof I hereunto affix my 25 signature in the presence of two witnesses.

JOHN TREGONING.
